US0D1042739S

(12) **United States Design Patent** (10) **Patent No.:** **US D1,042,739 S**
(45) **Date of Patent:** **** Sep. 17, 2024**

(54) **CONTAINER**

(71) Applicant: **S. C. Johnson & Son, Inc.**, Racine, WI (US)

(72) Inventors: **Julie L. Bates**, Franklin, WI (US); **James R. Crapser**, Racine, WI (US); **Thomas A. Helf**, New Berlin, WI (US); **Joel Kramka**, Madison, WI (US); **Casey Frett**, Madison, WI (US); **Katlyn Garcia**, McFarland, WI (US); **Richard A. Batton**, Racine, WI (US); **Evan A. Sparks**, Madison, WI (US)

(73) Assignee: **S. C. Johnson & Son, Inc.**, Racine, WI (US)

(**) Term: **15 Years**

(21) Appl. No.: **29/848,720**

(22) Filed: **Aug. 4, 2022**

Related U.S. Application Data

(63) Continuation of application No. 29/731,994, filed on Apr. 20, 2020, now Pat. No. Des. 960,319, which is (Continued)

(57) **CLAIM**

The ornamental design for a container, as shown and described.

DESCRIPTION

FIG. 1 is an isometric view of a top, front, and right side of an ornamental design for a container;

FIG. 2 is a front elevational view of the container of FIG. 1; FIG. 3 is a rear elevational view of the container of FIG. 1; FIG. 4 is a left side elevational view of the container of FIG. 1; and,

FIG. 5 is a top plan view of the container of FIG. 1. The dash-dash-dash broken lines are included for the purpose of illustrating portions of the container that form no part of the claimed design. The dash-dot-dash broken lines illustrate boundary lines and form no part of the claimed design.

1 Claim, 5 Drawing Sheets

Related U.S. Application Data

a continuation of application No. 29/630,107, filed on Dec. 19, 2017, now Pat. No. Des. 884,833, which is a continuation of application No. 29/578,444, filed on Sep. 21, 2016, now Pat. No. Des. 809,097.
